UNITED STATES PATENT OFFICE.

FRANCIS X. DUSSEAU AND BERNARD F. KIRK, OF DETROIT, MICHIGAN.

DENTAL MEASURING-TOOL.

No. 825,896.

Specification of Letters Patent.

Patented July 17, 1906.

Application filed December 7, 1905. Serial No. 290,694.

To all whom it may concern:

Be it known that we, FRANCIS X. DUSSEAU and BERNARD F. KIRK, citizens of the United States, residing at Detroit, county of Wayne, State of Michigan, have invented a certain new and useful Improvement in Dental Measuring-Tools; and we declare the following to be a full, clear, and exact description of the invention, such as will enable others skilled in the art to which it pertains to make and use the same, reference being had to the accompanying drawings, which form a part of this specification.

This invention relates to dental measuring-tools, the object of the invention being to provide an accurate measure to determine the distance around a solid body—as, for example, around a tooth.

In the drawings, Figure 1 is a perspective of the complete tool. Fig. 2 is a longitudinal section. Fig. 3 is an elevation of the end of the tool shown on a larger scale.

The tool consists of a bar 2, preferably round and provided with a longitudinal groove 3, that extends from end to end of the bar, forming a deep track or guide for a slide that travels therein. Preferably the slide has a band-like body 5, that engages around the bar, and the end of which, 6, engages in the groove 3. The end of a flexible strap 7 is secured to the slide 5, and another end of the same strap 7 is secured to the end of the bar 3. To make the fastening, there is cut a groove 8, inclined to the axis of the rod, and in this groove the end of the strap 7 engages. Preferably the strap is made of a flexible metal, and the end of it is secured to the rod in the groove 3 by a drop of solder or any suitable fastening. The end of the strap which engages with the slide 6 is sharply bent and passed through an opening 9, so that the part in front of the opening 9

is at the one side of the depending wing 6 and another part of the strap 7 is at another side of the wing 6. This method of construction causes the flexible strap to engage with considerable frictional resistance against the sides of the groove 3, requiring some force to move the slide along the bar. At the end of the bar farthest removed from the projecting or loop part of the strap is a projection 10, the main use of which is to serve as an abutment or handle to be used as a rest for the finger or a grip for the finger in manipulating the tool. A similar projection 4 extends from the slide 5.

The bar is graduated along its length with any appropriate system of graduation.

In operation the movement of the slide 5 along the bar varies the size of the loop in the strap 7, and the graduation on the bar determines the reading which is to be given to the projecting loop.

What we claim is—

In combination with a grooved bar, a slide member engaging thereabout and with one end portion reaching thereinto and its other end portion projecting outwardly from said bar, said slide being adapted to frictionally resist its travel therealong, a flexible strap having one portion fixed to an end of said bar and the other portion fixed to said slide member, the intermediate portion of said strap extending beyond the end of said bar and being adapted to encircle an object, substantially as described.

In testimony whereof we sign this specification in the presence of two witnesses.

FRANCIS X. DUSSEAU.
BERNARD F. KIRK.
